US0D1113071S

(12) United States Design Patent (10) Patent No.: US D1,113,071 S
(45) Date of Patent: * Feb. 17, 2026

(54) NECKWEAR ACCESSORY

(71) Applicant: WG Products LLC, Chicago, IL (US)

(72) Inventors: James Poulos, Northbrook, IL (US);
Peter F. Andreou, Northbrook, IL (US); Katelyn Poulos, Northbrook, IL (US)

(73) Assignee: WG Products LLC, Chicago, IL (US)

() Term: 15 Years

(21) Appl. No.: 29/928,898

(22) Filed: Feb. 16, 2024

Related U.S. Application Data

(63) Continuation of application No. 18/216,306, filed on Jun. 29, 2023, which is a continuation-in-part of application No. 17/733,060, filed on Apr. 29, 2022, now Pat. No. 12,000,652.

(57) CLAIM

The ornamental design for a neckwear accessory as shown and described.

DESCRIPTION

FIG. 1 is a front perspective view of a neckwear accessory showing our new design; and,
FIG. 2 is a front view thereof.

The small dotted and large broken lines depict stitching which forms no part of the claimed design. The thin long broken lines depict portions of the neckwear accessory that form no part of the claimed design.

1 Claim, 2 Drawing Sheets
